FIG. 3.

UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,114,198.

Specification of Letters Patent.

Patented Oct. 20, 1914.

Application filed February 17, 1914. Serial No. 819,258.

To all whom it may concern:

Be it known that I, ARTHUR W. SMITH, a citizen of the United States, and resident of the borough of Manhattan, city of New York, in the county of New York and State of New York, have invented certain new and useful Improvements in Type-Writing Machines, of which the following is a specification.

10 My invention relates to paper feeding and controlling mechanism for typewriting machines and its general object is to provide improved mechanism of the character stated and which is suitable for a variety of uses.

15 More specifically the present invention has for its object the improvement of the tally strip mechanism disclosed in the prior application of Clio B. Yaw, Serial No. 762,114, filed April 18, 1913.

20 To the above and other ends my invention consists in the features of construction, combinations of devices and arrangements of parts hereinafter described and particularly pointed out in the claims.

25 In the accompanying drawings, Figure 1 is a fragmentary front elevation showing the upper part of a No. 11 Remington type-writing machine embodying my invention. Fig. 2 is a plan view of a stationary cam member comprised in the present form of my invention. Fig. 3 is a fragmentary end elevation of the upper part of said Remington machine, some parts being shown in section. Fig. 4 is a fragmentary perspective detail view. Fig. 5 is a fragmentary end view partly in section of some of the tally line spacing devices shown in different positions from which they appear in Fig. 3.

30 As appears from Figs. 1 and 3 the main frame of said Remington machine comprises posts 1 supporting a top plate 2 from which rise lugs 3, said lugs having secured to them grooved guide rails 4 that coöperate 45 through anti-friction balls 5 with a front bar 6 and rear bar 7 of a carriage truck which further includes end bars 8 connecting said front and rear bars. Shiftably connected with said truck by devices 9 is a platen frame or carrier comprising end bars 50 or plates 10 and cross rods or bars 11 and 12, said platen frame and its supporting truck constituting a traveling platen carriage. The end bars 10 provide bearings for shafts 13 and 14 on which is mounted a two-

part or divided platen comprising a main section or element 16 at the right of which and coaxial therewith is the supplemental or tally section 17 of the platen. Supported fixedly within the main platen section and extending rightwardly therefrom is a sleeve or tube 16^a on which the tally platen section 17 is rotatably mounted. To the right-hand end portion of said sleeve 16^a is operatively connected the line spacing ratchet wheel 18 of the main platen section. At its right-hand end the tally platen section 17 has fixed to it a platen head which is formed peripherally with gear teeth, thus constituting said head a spur gear wheel 19 rigid with the section 17. Arranged at the right of the gear 19 is a knurled annulus or paper feeding device 20 which is fixed to the right-hand end portion of the tube or sleeve 16^a and is thereby connected to turn at all times with the platen section 16, said annulus being of substantially the same diameter as said platen section. To the right of the annulus 20 is a spur gear wheel 21 which is adapted to turn freely on the aforesaid tube, the gear 21 having teeth corresponding with the gear wheel 19. To the right of the gear wheel 21 and fixedly connected therewith is a ratchet wheel 22 which corresponds with the ratchet wheel 18 which is contiguous to it at the right. It will be understood, however, that the ratchet wheel 22 is adapted to turn loosely on the tube 16^a. Paper feeding devices of the usual Remington construction comprising pressure rollers 23 and 24 coöperate with the main platen section, and additional paper feeding devices comprising short roller sections, the forward one 25 whereof is indicated in Fig. 1, coöperate with the annulus 20 and are controlled by the usual releasing lever (not shown) which controls the pressure rollers 23 and 24. In the present instance no feed rollers are provided for coöperation with the platen section 17. It will be understood that the main platen section and its feeding devices are adapted to feed a main sheet which is or may be arranged in superposed relationship with the tally sheet or strip that is fed over the tally platen, and that in the case of a long main sheet which has a margin extending rightward beyond the tally platen, the annulus 20 and its pressure rolls coöperate with the right-hand marginal portion of said main sheet to assist the main

platen section and its feeding devices to feed said sheet evenly and truly.

The tally strip mechanism is mounted on a supporting frame comprising upright arms 26 and 27 and a connecting cross bar 28. Said support may be mounted on the cross rod 12 of the platen frame and fixed to said rod near the right-hand end thereof so that the rotary holders for the tally work sheet which are mounted on said frame are above the tally platen section 17. The delivery roll holder or tally strip spool 29 is mounted on a rod or shaft 30 and the other tally strip spool or receiving roll holder 31 is mounted on a rod or shaft 32 below the delivery holder, the shaft 32 bearing rotatably in the arms 26 and 27. Arranged between the right-hand end of the roll holder 31 and the supporting arm 26 is a pinion 33 which is secured to the shaft 32 as by a pin 34 passing transversely through the hub of said pinion and through said shaft. Outside the arm 26 a similar pinion 35 is mounted on the outwardly projecting end 25 of the shaft 32 and is suitably fixed thereto. The extreme end portion of the shaft, indicated by 32^a, may be reduced in diameter and flattened at opposite sides to receive a short crank arm 36 which is formed with a hole 30 having two straight opposite sides that fit over the portion 32^a, said crank arm being secured in place by a headed screw 37. A smaller screw 38 passes through the outer end of the crank arm and is threaded into 35 the pinion 35, thus fixedly connecting said pinion with the shaft 32. The pinions 33 and 35 are respectively connected through pinions or idlers 39 and 40 with the gear wheels 19 and 21, said idlers being preferably mounted to rotate loosely on the frame rod 12. It will be observed that two parallel trains of gear devices are provided, said trains being arranged at opposite sides of the annulus 20 and that said trains connect the ratchet wheel 18 with the receiving roll holder 31 and the tally platen section 17.

The parts heretofore described correspond or may correspond, except for minor differences, with the construction disclosed in Clio B. Yaw's said prior application, Serial No. 762,114. There is one difference of importance, however, between the present construction as thus far described and said prior construction, namely, no tally feeding devices are provided for co-operatively engaging with the tally platen section in the present instance, the tally being advanced or fed by the turning of the receiving roll holder 31 on which the tally strip or right-hand work sheet is wound. The turning of the tally platen section 17 simultaneously with the turning operation of the roll holder 31 through the gear connections between the 60 two parts facilitates the advance movement

of the tally strip which does not have to drag over a motionless platen section or paper support. Said platen section turns as the tally strip advances but this turning of the tally platen section does not, properly speaking, result in a feeding operation of the tally. The two platen sections or work sheet supports and the tally receiving holder are adapted to be actuated by novel line spacing devices comprising sets of mechanisms operative by a single hand piece or actuator, these devices being controllable by novel controlling means including a preventive device so that either the main platen section 16 may be advanced alone and independently of the other platen section and the roll holder 31, or on the other hand, the section 16 together with the tally platen section and the holder 31 may be turned or line spaced together. Spring mounted roller detents 41 and 42 coöperate respectively with the ratchet wheels 18 and 22 to maintain them and the parts respectively connected and controlled by them in adjusted positions following and between line spacing operations. The sets or trains of paper advancing mechanisms aforesaid comprise pawls or pawl members 43 and 44 arranged side by side and adapted for coöperation respectively with the ratchet wheels 18 and 22, said pawl members being loosely suspended from a bearing in the form of a headed shouldered screw or stud 45 which is fixedly secured by a nut 46 to a radial supporting arm 47 which is loosely mounted on a sleeve 48 fixed to the right-hand end plate 10 of the platen frame and concentric with the platen axle 14 which passes through it. The two pawls are loosely confined between the head of the screw 45 and the arm 47 but are spaced leftward away from said arm by the hub portion 43^a of the pawl member 43. The mounting of the pawl members 43 and 44 comprising the arm 47 is like that of the Remington machine aforesaid and said arm 47 may be controlled as in said machine for varying the extent of line spacing movement of said pawl members. The pawl members are connected by a wire spring 49, the lower end of which is anchored to the outer face of the pawl member 43 by a screw 50. From said screw the spring extends forward, leftward and upward over the front edge or face of the pawl member 43 and then is bent leftward forming a shoulder 49^a, the shoulder portion extending partly over the front edge of the pawl member 44. The extreme upper end portion of the spring is bent backward and engages in a hole 51 in the pawl member 44. The tendency of said spring is constantly to press said pawl member 44 rearward and when it is free to exert its pressure it will move said pawl member until the limit of such movement is reached as determined by the engagement of 125

the shouldered portion 49^a of the spring with the front face of the pawl member 43. The independent movement of the pawl member 44 under the influence of the spring is, however, controlled and regulated by devices hereinafter described.

The teeth or engaging portions 43^x and 44^x of the pawls 43 and 44 stand normally under all conditions away from or disengaged from their respective ratchet wheels. Movements of the pawl members by which they are caused to engage with their ratchet wheels and communicate line spacing advance movements thereto are caused by actuating devices which are connected directly to the pawl member 43 and which preferably correspond with the actuating devices of the Remington No. 11 machine, although certain slight differences may be noted, viz., the pawl member 43 has a direct pin-and-hole, lost motion connection with the supporting arm 47, a pin or stud 52 extending laterally rightward from said pawl member and engaging loosely in a hole 53 in said arm; and furthermore the forwardly extending actuating link 54 is pivotally connected at 55 directly to the pawl member 43 instead of through an intermediate member as in the regular Remington construction aforesaid. Said link 54 extends forward, its forward end being pivotally connected to the upper arm of a bell crank 56 pivoted at 57 to the right-hand end bar 8, the other and shorter arm of said bell crank being connected by a link 58 with a crank arm 59 secured by a screw 60 to the rear end of a rock shaft 61 bearing in a housing 62 on the end bar 8, said housing containing a line spacing restoring spring 63 coiled around said rock shaft. Forward of said housing the rock shaft is shaped to provide a downwardly extending hand-piece, handle, lever arm or device 64 which when swung or pressed rightward operates through the described train of connections to actuate operatively the pawl member 43 and at times also the pawl member 44. Said hand piece or actuator 64 also restores the carriage from left to right.

Means are provided for so controlling the line spacing mechanism that when the left-hand platen section is in the printing field it alone will receive step-by-step line spacing movements from actuations of the hand-piece 64, while when the right-hand platen section is at the printing point an actuation of said hand-piece will operate to advance both platen sections as well as the tally receiving roll holder together. As a result the main sheet that is fed over the left-hand platen section will be advanced at each line spacing actuation while the tally strip will be advanced only intermittently or when it is in the printing field, these results being obtained by operating a single

actuator that is common to the paper advancing means associated with both the main work sheet and also the tally work sheet. In Fig. 3 the main sheet is indicated by the reference character p and the tally strip by p' . The tally strip p' is led off from the rear of the delivery roll holder and down around the tally platen section and up at the front thereof to the front side of the receiving roll holder to which it is suitably secured, passing between the cutting blade 65 and slotted bar 66 of a paper shearing device.

Preferably a carbon or transfer strip is wound up with the tally strip and is fed therewith, said carbon strip being indicated by the reference character p^2 . It will be understood that the carbon strip is outside the tally strip and that the carboned face is inward or in contact with the outer face of the tally strip. The main sheet p which in ordinary commercial writing is an invoice or bill, the totals or other special data whereof are to be transferred to the tally strip through the carbon strip, receives impressions of the types through the usual inking ribbon (not shown). Said main sheet is fed down around the main section or left-hand end portion of the platen between it and the feed rollers 23 and 24 and its right-hand portion overlies or is superposed on the carbon strip p^2 and the tally strip p' , in some instances as has been stated extending so far rightward that its right-hand margin is brought within the control of the annulus 20 and its coöperating rolls. That portion of the main sheet which is fed around the platen portion or section 16 receives the items which are not to be duplicated on the tally strip and these items are preferably written at line space intervals, the main sheet being advanced by line space movements of the left-hand platen section through the actuation of the hand-piece 64 and the consequent coöperation of the pawl member 43 and the ratchet wheel 18, the latter it will be recalled being operatively connected with the platen section 16.

In order to prevent the operation of the pawl member 44 on its ratchet wheel 22 while the regular line spacing of the main sheet is taking place, preventive or controlling devices are provided to coöperate with a projection or pin 67 which projects laterally leftward from the lower end of the pawl member 44. Said devices comprise a finger 68 with the front face whereof the pin 67 is adapted to coöperate. This finger 68, the details of which clearly appear in Fig. 4, is preferably made of sheet metal and is curved to conform generally to the curve of the platen and the line spacing ratchet wheels. It extends upward at the front of the annulus 20 and the gear wheel 21 and at its lower end is bent around and fixedly secured to a squared rock shaft 69, 130

this rock shaft being the same as is usually provided on the Remington machine for supporting the right-hand paper finger. The usual paper finger is replaced in the present instance by the finger 68 which not only exercises a controlling function on the pawl member 44 but also is adapted to act as a paper guide to properly direct the right-hand marginal bill sheet into coöperation with the annulus 20. The rock shaft 69 that supports said finger 68 is rotatably mounted, the left-hand end portion of said rock shaft bearing in a bracket 70 screwed to the front of the platen frame bar 11 (Fig. 1) while the right-hand end portion of said rock shaft bears in the right-hand end bar 10 and projects slightly outward beyond said end bar. The projecting end portion has fixed to it by a screw 71 a rearwardly extending crank arm 72 to the free end of which is anchored the lower end of a coiled draw spring 73, the upper end of said draw spring, being anchored to one of the platen shift devices 9. Said draw spring tends constantly to swing the crank arm 72 upward, this upward movement being limited by a stop pin 74 projecting outward from the end bar 10 with which stop pin the crank arm is normally in engagement as shown in Fig. 3. The action of the spring 73, it will be understood, tends to turn the upper faces of the rock shaft 69 forward and to swing the finger 68 forward so that said finger is normally maintained away from the annulus 20 as shown in said Fig. 3. Said finger operating through the pin 67 holds the pawl member 44 forward and maintains it forward during the actuation of the hand piece 64, the pin 67 during such actuation riding up over the outer face of the finger 68 which is so shaped and disposed that during the line spacing operation of the pawl member 43 the pawl member 44 will be maintained out of engagement with its ratchet wheel 22 so that it will be ineffective to advance said ratchet wheel and the connected parts and consequently will not affect the associate work sheet or tally strip. It will be understood that the spring 49 operates the spring 73 and tends to swing the pawl member 44 inward toward its ratchet wheel but the spring 49 is considerably weaker than the spring 73 so that it is not effective to overcome the latter.

In order to overcome the spring 73 and render the spring 49 effective to swing the pawl member 44 into a normal position such that it will act on its ratchet wheel when the hand-piece 64 is actuated, devices are provided for automatically swinging the finger or preventive device 68 rearward so as to render it ineffective and cause it to release the pin 67 and the pawl member 44. Said devices operate automatically during traveling movements of the carriage or platen

carrier and at a predetermined point in the run of the carriage toward the left, becoming effective as the platen portion or section 16 leaves the printing field and the left-hand platen portion or section 17 over which is supported the tally strip and the right-hand portion of the bill sheet enters the printing field. The automatic devices comprise a short finger or projection 75 which is bent around and suitably secured to the rock shaft 69 to the right of the finger 68 as appears from Fig. 4. The finger 75 normally inclines forward and downward as shown in Fig. 3 and is adapted to coöperate with a stationary cam member or actuating device 76 which is shown in detail in Fig. 2. Said cam member is formed with slots 77 which receive screws 78 by which the cam member is adjustably secured to the top plate of the machine. Said cam member is provided with a rearwardly off-set portion 79, the right-hand end of which is inclined downward as indicated at 80, forming a cam which is in the path of the finger 75. This cam is so arranged that the finger 75 will engage with it when the traveling carriage has moved so far to the left that the left-hand portion of the platen section 17 has entered the printing field or been brought opposite the point at which the type bars strike when actuated. After the finger engages with the inclined face 80 farther leftward movement of the carriage will cause the finger to ride up over said face on to the off-set portion 79 and this action of the finger will turn the rock shaft 69 and swing the finger 68 toward the platen, bringing the parts to the position shown in Fig. 5. This movement of the finger 68 withdraws it from the pin 67 which leaves the pawl 44 free to be swung rearward by its spring 49 until arrested by the contact of the off-set portion 49^a with the front face of the pawl member 43 as shown in Fig. 5. With the pawl members thus positioned an actuation of the hand-piece 64 will effectively actuate both pawl members, causing them to coöperate with their respective ratchet wheels and simultaneously advance both platen sections and also the tally receiving roll holder, thus advancing or line spacing both the main and tally work sheets. The off-set portion 79 is of such length that it will operate through the finger 75 to render the pawl member 44 operative so long as the tally strip remains in the printing field and until the end of the carriage travel toward the left is reached. When the carriage is retracted the finger 75 will move backward along and over the off-set portion and down over the incline 80 and the spring 73 will become effective to swing the finger or preventive device 68 forward to the Fig. 3 position where it will maintain the pawl member 44 in inoperative position.

Various changes may be made without departing from the scope of my invention.

What I claim as new and desire to secure by Letters Patent, is:—

5. 1. In a typewriting machine, the combination of a platen carriage, a divided platen mounted thereon and comprising a plurality of sections adapted to receive separate work sheets, sets of line spacing devices for advancing said work sheets, each set comprising a line spacing wheel, pawl members one for each line spacing wheel, a single means for actuating said pawl members, and means separate from one of said pawl members 10 and effective on the other pawl member for preventing the operation of said other pawl member when said single means is actuated. 70
2. In a typewriting machine, the combination of a platen carriage, a divided platen mounted thereon and comprising a plurality of sections adapted to receive separate work sheets, sets of line spacing devices for advancing said work sheets, each set comprising a line spacing wheel, pawl members one for each line spacing wheel, a single means for actuating said pawl members, a device 75 for preventing the operation of one of said pawl members, and mechanism brought into play during the traveling movements of said platen carriage to render said device effective and ineffective on its associate pawl member, said mechanism operating at predetermined points in the travel of the carriage in one direction to throw said preventive device out of operation and at a predetermined point in the travel of the carriage in the opposite direction to permit said device to return to operative position. 80
20. 3. In a typewriting machine, the combination of a platen carriage, a divided platen mounted thereon and comprising a plurality of sections adapted to receive separate work sheets, sets of line spacing devices for advancing said work sheets, each set comprising a line spacing wheel, pawl members one for each line spacing wheel, a single means for actuating said pawl members, a device 85 for preventing the operation of one of said pawl members, and mechanism brought into play during the traveling movements of said platen carriage to render said device effective and ineffective on its associate pawl member. 90
25. 4. In a typewriting machine, the combination of a platen carriage, a platen mounted thereon and adapted to receive a plurality of work sheets, sets of line spacing devices for advancing said work sheets, each set comprising a line spacing wheel, engaging members one for each line spacing wheel, a single means for actuating said members, a device for preventing the operation of one of said members, and mechanism brought 95 into play at predetermined points in the traveling movements of said platen carriage to render said device effective and ineffective on its associate member. 100
30. 5. In a typewriting machine, the combination of a platen carriage, a divided platen mounted thereon and comprising a plurality of sections adapted to receive separate work sheets, sets of line spacing devices for advancing said work sheets, each set comprising a line spacing wheel, pawl members one for each line spacing wheel, a single means for actuating said pawl members, and means 105 controllable by said traveling carriage to throw one of said pawls into and out of use. 110
35. 6. In a typewriting machine, the combination of a platen carriage, a platen thereon adapted to receive a plurality of separate work sheets, sets of pawl and ratchet mechanisms, each set being adapted to advance one of said work sheets, a single actuator for said sets, and means controllable by said traveling carriage to throw one of said pawls into and out of the effective control of said actuator. 115
40. 7. In a typewriting machine, the combination of a platen carriage, a platen thereon adapted to receive a plurality of separate work sheets, sets of pawl and ratchet mechanisms, each set being adapted to advance one of said work sheets, a single actuator for said sets, and means controllable by said traveling carriage to throw one of said pawls into and out of the effective control of said actuator. 120
45. 8. In a typewriting machine, the combination of a platen carriage, a platen thereon adapted to receive a plurality of separate work sheets, sets of pawl and ratchet mechanisms, each set being adapted to advance one of said work sheets, a single actuator for said sets, and means controllable by said traveling carriage to throw one of said pawls into and out of the effective control of said actuator. 125
50. 9. In a typewriting machine, the combination of a traveling platen carrier, a divided cylindrical platen journaled thereon and comprising a plurality of sections having a common axis of rotation and adapted to receive separate work sheets, paper advancing means for one of said work sheets including a line space wheel, a pawl operative upon said line space wheel, paper advancing means for the second of said work sheets including a second line space wheel, a pawl operative on said second line space wheel, a single actuator for both of said pawls, and means including a device mounted on a stationary support for throwing one of said pawls into and out of use. 130
55. 10. In a typewriting machine, the combination of a pair of traveling platen sections

arranged end to end and supporting separate work sheets, line spacing devices for one of said work sheets comprising a pawl, an actuator effective at each operation thereof on said pawl to cause it to operate said line spacing devices, other line spacing devices for the second of said work sheets including a second pawl, means for preventing the effective operation of said second pawl, and means for automatically rendering said actuator effective to operate said second pawl when said second work sheet is brought into the printing field.

11. In a typewriting machine, the combination of a plurality of traveling platen sections adapted to receive separate work sheets, separate sets of step-by-step line spacing devices each set for advancing one of said work sheets, a hand piece operative on each of said sets, and means for preventing the effective operation of one of said sets by said hand piece except when the work sheet which it is operative to advance is in the printing field.

12. In a typewriting machine, the combination of a plurality of rotatable traveling platen sections adapted to receive separate work sheets, separate sets of pawl and ratchet devices each set for advancing one of said work sheets, a single actuator for said sets, and means for preventing an actuation of one of said sets except when the work sheet which it is operative to advance is in the printing field.

13. In a typewriting machine, the combination of a plurality of traveling platen sections adapted to receive separate work sheets, separate sets of step-by-step line spacing devices each set for advancing one of said work sheets, a hand piece operative on each of said sets, devices for preventing the effective operation of one of said sets by said hand piece while the work sheet controlled by said set is out of the printing field, and other devices operating automatically at a predetermined point in the travel of the carriage to render said first-mentioned devices ineffective.

14. In a typewriting machine, the combination of a plurality of traveling platen sections, separate sets of step-by-step line spacing devices, one for each of said sections, a single hand piece operative on each of said sets, means for preventing the effective operation of one of said sets by said hand piece while the platen section connected with said set is out of the printing field, and means operative automatically when the platen section last referred to enters the printing field to throw said preventive means out of use.

15. In a typewriting machine, the combination of a platen carrier, a platen mounted thereon and adapted to receive a plurality of separate work sheets, mechanism for advanc-

ing one of said work sheets comprising a line space wheel, other mechanism for advancing another of said work sheets including a second line space wheel, pawls each associated with one of said line space wheels, a movable support common to said pawls, a single hand actuated train of devices for operating said pawls, a device for preventing one of said pawls from coöperating with its line spacing wheel, and means for moving said device to an ineffective position.

16. In a typewriting machine, the combination of a platen carrier, a platen thereon supporting a plurality of separate work sheets, mechanism for advancing one of said work sheets comprising a line space wheel, other mechanism for advancing another of said work sheets including a second line space wheel, pawls each associated with one of said line space wheels, a movable support common to said pawls, a single hand actuated train of devices for operating said pawls, a device for preventing one of said pawls from coöperating with its line spacing wheel, and means for moving said device to an ineffective position, said moving means comprising an adjustable cam on the frame of the machine.

17. In a typewriting machine, the combination of a platen carrier; a sectional platen thereon, trains of line spacing devices for the platen sections, said trains including separate pawls one for each section, and a common actuator for said pawls; means including opposing springs operative on one of said pawls, one spring tending to move the pawl to effective position and the other to hold it out of effective position, the latter spring being stronger; and means for overcoming the stronger spring and rendering the weaker spring operative to move said pawl to effective position.

18. In a typewriting machine, the combination of a platen over which is fed a plurality of work sheets, line spacing devices including two ratchets and two coöperating pawls arranged side by side, one pawl and ratchet being effective for advancing one of said work sheets and the other for advancing another of said work sheets, a spring connecting said pawls and tending constantly to move one of them toward its ratchet wheel, said spring being provided with a stop device for limiting such movement, spring pressed means normally overcoming said first recited spring, and means for rendering said spring pressed means ineffective.

19. In a typewriting machine, the combination of a platen carrier; a sectional platen thereon; trains of line spacing devices for the platen sections, said trains including separate pawls one for each section, and a common actuator for said pawls; a spring connecting said pawls and tending to

move one of them to effective position; devices including a second and stronger spring constantly tending to move the last named pawl to ineffective position; and means for overcoming said stronger spring and rendering the first recited spring effective, said means operating automatically at a predetermined point in the travel of said carrier.

20. In a typewriting machine, the combination of a platen carrier, a platen adapted to receive a plurality of work sheets, pawl and ratchet mechanism for advancing said work sheets, said devices comprising a plurality of pawls, a common actuator for said pawls, means including opposing springs operative on one of said pawls, one spring tending to move said pawl to effective relationship with its associate ratchet and the other spring to hold it out of effective relationship, the last named spring being the stronger, and means for overcoming said stronger spring and rendering the weaker spring operative to move said pawl to effective position.

25. 21. In a typewriting machine, the combination of a platen carrier, a platen adapted to receive a plurality of work sheets, pawl and ratchet mechanism for advancing said work sheets, said devices comprising a plurality of pawls, a common actuator for said pawls, means including opposing springs operative on one of said pawls, one spring tending to move said pawl to effective relationship with its associate ratchet and the other spring to hold it out of effective relationship, the last named spring being the stronger, and means operating automatically at a predetermined point in the travel of said carrier to overcome said stronger spring and render the first recited spring effective.

22. In a typewriting machine, the combination of a traveling platen carrier, a main platen section thereon, a tally platen section thereon, trains of devices for turning each platen section step-by-step, means for preventing the operation of the train associated with the tally platen section when said tally platen section is out of the printing field, and means for overcoming said preventive means and rendering the same inoperative when said tally platen section is in the printing field.

23. In a typewriting machine, the combination of a traveling platen carrier, a platen thereon supporting a main work sheet, tally strip devices on said carrier for supporting a tally strip, the tally strip passing around the platen, trains of step-by-step line spacing devices for said main work sheet and said tally strip, means for preventing the operation of the line spacing train associated with said tally strip when the tally strip is out of the printing field, and means for rendering said preventive means

inoperative when the movement of the platen carrier brings the tally strip into the printing field.

24. In a typewriting machine, the combination of a traveling platen carrier, a platen thereon supporting a main work sheet, tally strip devices on said carrier including a rotary tally receiving holder, line spacing devices for the main work sheet including a ratchet wheel operatively connected with said platen, a pawl operative on said wheel, devices for turning said rotary holder to advance the tally strip, said last named devices including a second line spacing wheel connected with said rotary holder, a second pawl operative on said second wheel, and a single actuator operative on both said pawls.

25. In a typewriting machine, the combination of a traveling platen carrier, a platen thereon supporting a main work sheet, devices for supporting a second work sheet that passes around said platen, said devices including a rotary work receiving holder, line spacing mechanism for the main work sheet, other mechanism for turning said holder to advance said second work sheet, and a common actuator for said mechanisms.

26. In a typewriting machine, the combination of a traveling platen carrier, a platen thereon supporting a main work sheet, devices for supporting a second work sheet that passes around said platen, said devices including a rotary work receiving holder, line spacing mechanism for the main work sheet, other mechanism for turning said holder to advance said second work sheet, a common actuator for said mechanisms, and means for preventing the operation of said other mechanism when said actuator is operated.

27. In a typewriting machine, the combination of a traveling platen carrier, a platen thereon supporting a main work sheet, devices for supporting a second work sheet that passes around said platen, said devices including a rotary work receiving holder, line spacing mechanism for the main work sheet, other mechanism for turning said holder to advance said second work sheet, a common actuator for said mechanisms, and means including a preventive finger for throwing said other mechanism out of use when said actuator is operated, said finger acting also as a guide for said main work sheet.

28. In a typewriting machine, the combination of a platen, paper feeding and guiding devices for a work sheet that is fed around said platen, said devices including a paper guide, means operative to advance another work sheet and including a hand piece, and devices for preventing the operation of said paper advancing means when

said hand piece is actuated, said preventive devices including said guide.

29. In a typewriting machine, the combination of a traveling platen carrier, a platen thereon supporting a main work sheet, devices for supporting a second work sheet that passes around said platen, said devices including a rotary work receiving holder, line spacing mechanism for the main work sheet, other mechanism for turning said holder to advance said second work sheet, a common actuator for said mechanisms, means for preventing the operation of said other mechanism when said actuator is operated, and means for throwing said preventive means out of operation so that said actuator may be effective to operate both said mechanisms.

30. In a typewriting machine, the combination of a traveling platen carrier, a platen thereon supporting a main work sheet, devices for supporting a second work sheet that passes around said platen, said devices including a rotary work receiving holder, line spacing mechanism for turning said platen to advance the main work sheet, other mechanism for turning said holder to advance said second work sheet, a common actuator for said mechanisms, and means for preventing the operation of said other mechanisms when said actuator is operated, and means operating automatically at a predetermined point in the carriage travel to throw said preventive means out of operation.

31. In a typewriting machine, the combination of a traveling platen carrier, a platen thereon supporting a main work sheet, devices including a rotary work receiving holder for supporting a second work sheet that passes around said platen, line spacing mechanism for the main work sheet, other mechanism for turning said holder to advance said second work sheet, a common actuator for said mechanisms, means for preventing the operation of said other mechanism when said actuator is operated, and means operating automatically when said second work sheet enters the printing field to render said preventive means inoperative.

32. In a typewriting machine, the combination of a traveling platen carrier, a platen thereon supporting a main work sheet, devices for supporting a second work sheet including a rotary work receiving holder, line spacing mechanism for the main work sheet, other mechanism for turning said holder to advance said second work sheet, a single actuator common to said mechanisms, and means for rendering said actuator effective on one only of said mechanisms when one of the work sheets is in the printing field, said actuator operating on both said mechanisms when the other work sheet is in the printing field.

33. In a typewriting machine, the combination of a traveling platen carrier, a divided platen thereon comprising a main section and a tally section arranged end to end, paper feeding devices coöperative with said main section for feeding a main work sheet, tally strip devices including delivery and receiving roll holders, the tally strip passing around the tally section from one roll holder to the other, a ratchet wheel operatively connected with the main platen section, a second ratchet wheel operatively connected with the receiving roll holder, pawls coöperative with said ratchet wheels, and devices including a single line space handle for operating both said pawls.

34. In a typewriting machine, the combination of a divided platen comprising a main section and a tally section, paper feeding devices coöperative with said main section for feeding a main work sheet, tally strip devices including a delivery roll holder, and a receiving roll holder, the tally strip passing around said tally section from one roll holder to the other, a ratchet wheel operatively connected with the main platen section, a second ratchet wheel, connections between said second ratchet wheel and both said receiving roll holder and the tally platen section, pawls coöperative with said ratchet wheel, devices including a single line space handle for actuating both said pawls, and means for throwing one of said pawls into and out of operative relationship with its associate ratchet wheel.

35. In a typewriting machine, the combination of a divided platen comprising a main section and a tally section, paper feeding devices coöperative with said main section for feeding a main work sheet, tally strip devices including a delivery roll holder and a receiving roll holder, the tally strip passing around said tally section from one roll holder to the other, a ratchet wheel operatively connected with the main platen section, a second ratchet wheel, connections between said second ratchet wheel and both said receiving roll holder and the tally platen section, a pawl for said first named ratchet wheel, a second pawl coöperative with said second ratchet wheel, a swinging finger coöperative with a projection on said second pawl to hold it out of operative relationship with its ratchet wheel, and a stationary cam device operative during the traveling movements of said platen to swing said finger to ineffective position and permit said second pawl to move into operative relationship with its ratchet wheel.

36. In a typewriting machine, the combination of a divided platen comprising a main section and a tally section, paper feeding devices coöperative with said main section for feeding a main work sheet, tally strip devices including a delivery roll holder

and a receiving roll holder, the tally strip passing around said tally section from one roll holder to the other, a ratchet wheel operatively connected with the main platen section, a second ratchet wheel, connections between said second ratchet wheel and both said receiving roll holder and the tally platen section, parallel gear trains, one train connecting said second ratchet wheel with 5 said receiving roll holder and the other train connecting said receiving roll holder with said tally platen section, pawls coöperative with said ratchet wheel, devices including a single line space handle for operating both said pawls, and means for rendering one of said pawls ineffective when said line space handle is operated.

37. In a typewriting machine, the combination of a traveling platen carrier, a divided platen thereon comprising a main section and a tally section arranged end to end, paper feeding devices coöperative with said main section for feeding a main work sheet, tally strip devices including delivery 20 and receiving roll holders, the tally strip passing around the tally section from one roll holder to the other, a ratchet wheel operatively connected with the main platen section, a second ratchet wheel operatively 25 connected with the receiving roll holder, pawls coöperative with said ratchet wheels, devices including a single line space handle for operating both said pawls, and means for rendering one of said pawls ineffective 30 when said line space handle is operated.

38. In a typewriting machine, the combination of a platen over which is fed a plurality of work sheets, line spacing devices including two pawl members, one pawl member being effective for advancing one of said 40 work sheets and the other pawl member for advancing another of said work sheets, a single actuator for operating said pawls, and means for rendering one of said pawl members ineffective when said line space handle is operated.

39. In a typewriting machine, the combination of a platen over which is fed a plurality of work sheets, line spacing devices including two pawl members, one pawl member being effective for advancing one of said work sheets and the other pawl member for advancing another of said work sheets, a single actuator for operating said pawls, and 50 means for rendering one of said pawl members ineffective when said line space handle is operated, said means comprising a pivot-

ed member operative on one of said pawl members to prevent it from entering into effective position, spring means tending to 60 maintain said pivoted member in operative position, and devices for overcoming said spring means and turning said member on its pivot to ineffective position.

40. In a typewriting machine, the combination of a traveling platen carrier, a platen thereon over which is fed a plurality of work sheets, line spacing devices including two pawls one pawl effective for advancing one of said work sheets and another pawl 70 for advancing another of said work sheets, a single actuator for operating said pawls, a finger pivotally mounted on said platen carrier and engaging a projection on one of said pawls, a spring acting through said 75 finger to swing the pawl engaged thereby in one direction, a second and weaker spring tending to throw said pawl in the opposite direction, and means comprising a stationary device effective on said finger during the 80 travel of the carriage to overcome the stronger spring and render the weaker spring effective.

41. In a typewriting machine, the combination of a traveling platen carrier, a platen 85 thereon over which is fed a plurality of work sheets, line spacing devices including two pawls one pawl effective for advancing one of said work sheets and another pawl for advancing another of said work sheets, 90 a single actuator for operating said pawls, a rock shaft journaled on said traveling carrier, a finger secured to said rock shaft and engaging a projection on one of said pawls, a draw spring connected to said rock shaft 95 and effective on said finger to cause it to maintain the pawl having the engaged projection in ineffective position when actuated, a second and weaker spring connecting said pawls and acting in opposition to said draw 100 spring, and a stationary cam member coöperating with a projection on said rock shaft during traveling movements of the carriage to overcome said draw spring and render said finger ineffective to restrain the pawl 105 with which it engages.

Signed at the borough of Manhattan, city of New York, in the county of New York and State of New York, this 16th day of February, A. D. 1914
